ABSTRACT OF THE DISCLOSURE

There is described a photo-tube device which generates low frequency coherent oscillations due to an electron bunching effect caused by a periodic or discontinuous pattern of light falling on the cathode. There is a magnetic field applied to the photo-tube having a component of flux extending across the region between the anode and cathode. No electrical energy source is required in the circuit. The frequency of oscillation is proportional to changes in the intensity of the light falling on the phototube.

This invention relates to a unique oscillator circuit and, more particularly, is concerned with an oscillator circuit which is set in oscillation by incident radiant energy and which oscillates at a frequency which is dependent on the intensity of the incident radiant energy.

I have found that a vacuum photo-tube having a photo-emissive cathode can be used as an oscillator when suitably excited by a source of radiant energy, such as visible light and when the photo-tube is subjected to a suitably oriented magnetic field. While the nature of the phenomenon is not fully understood, it is believed to involve a rotating electron plasma within the region between the anode and the cathode electron emissive surfaces with which the electrodes are capacitively coupled. The rotation of the plasma is produced by the combined effect of the magnetic field and the effect on the emission of the cathode by the pattern of the incident light.

In brief, it has been found that an ordinary vacuum phototub having a semi-cylindrical cathode or emitter and a rod-shaped anode or collector can operate as an oscillator for generating an alternating signal of at least 300 millivolts in amplitude across a load resistor connected between the cathode and anode. No applied potential between the cathode and anode is necessary, although a potential of a few volts improves the stability and dynamic range of the oscillator. A magnetic field is required having a component of flux extending across the region between the anode and cathode which is generally parallel to the plane defined by the two parallel linear edges of the semi-cylindrical emitter of the photo-tube. When the cathode is partially illuminated by a strip, a pattern of strips, or spot of light or when a strong shadow is cast on the cathode which divides the cathode into at least two illuminated portions, strong oscillations are generated. It is believed that the separation of the cathode into separate emitting regions permits bunching of electrons in the magnetic field analogous to the bunching of electrons in the gaps of a magnetron anode.

There are, in fact, several possible modes of oscillation that have been observed. In the principal mode of operation, the output signal is sinusoidal and varies linearly in frequency with changes in light intensity. This mode is induced by a sharply defined beam of light striking a portion of the cathode. In another mode of oscillation, low frequency oscillations are produced which are non-sinusoidal in form and in which the frequency of oscillation is

2

much more sensitive to the strength of the magnetic field. This mode is induced by a shadow having more diffuse boundaries which divide the cathode into at least two larger illuminated areas. A very high frequency mode of oscillation has also been observed by using a choke across the output to effectively short out the low frequency oscillations.

For a more complete understanding of the invention, reference should be made to the accompanying drawings wherein:

FIGURE 1 is one embodiment of the present invention;

FIGURE 2 is another embodiment of the present invention;

FIGURE 3 is yet another embodiment of the present invention;

FIGURE 4 is a modified embodiment of the arrangement of FIGURE 3;

FIGURE 4a is an alternative arrangement to that of FIGURE 4.

FIGURE 5 is a graph illustrating the operating characteristics of the oscillator of the present invention;

FIGURE 6 is a schematic showing of a further modification of the present invention; and

FIGURE 7 is a graph illustrating another operating characteristic of the oscillator of the present invention.

Referring now to FIGURE 1, there is shown in outline an evacuated envelope 1 of a tube having a photo-emissive planar cathode or emitter 2 and a frame-like anode or collector 3, this collector lying generally in a plane parallel to the emitter 2. A magnetic field generally parallel to the plane of emitter 2 is established by means of a permanent magnet having poles 4 and 5 symmetrically placed on opposite sides of the tube. The emitter is illuminated by a narrow band of light 6 by any suitable means such as the combination of the light source L.S. and the slit in a stop 7. The shape and size of the collector 3 is preferably such that it casts no shadow on the emitter.

The emitter 6 may have any surface material which ejects electrons when subjected to radiation or atomic particles, and the light source L.S. may be any source of radiation or radio-active particles to which the emitter material is sensitive. For example, with a tube having a cesium coated emitter mentioned above and illuminated by white light from a low power incandescent lamp, it has been found that with a field of approximately 200 gauss, a pure sinewave output of up to 4 millivolts peak to peak is obtained.

There is a direct linear dependence of frequency upon the intensity of illumination on the emitter, as shown by FIGURE 5. With a given magnetic field, the amplitude of the signal remains the same for different values of light intensity within broad limits as long as the impedance of the load is matched with the impedance of the tube. The frequencies available from the device shown in FIGURE 1 range from about 10 c.p.s. to at least 100 kc./sec. depending only on change in light intensity. This makes the device useful for measurement of illuminance in terms of frequency. As shown in FIGURE 7, the frequency is inversely proportional to the strength of the magnetic field. Thus for strong magnetic fields, the frequency is not sensitive to small variations in magnetic field.

FIGURES 2 and 3 show variations of the light pattern and the electrode structure shown in FIGURE 1.

The device shown in FIGURE 2 differs from that shown in FIGURE 1 in that the stop 7' bears a plurality

of slits rather than only one. FIGURES 1 and 2 illustrate that the circuit oscillates in the same fashion with striated light, a single strip, or even a spot of light. The circuit does not oscillate with uniform illumination of the cathode.

FIGURE 3 shows an arrangement in which the electrodes take the usual form of a photo-tube, the emitter 12 being a portion of a cylinder. The magnetic field set up by magnetic poles 14 and 15 is generally transverse to the rod anode 13 and is parallel to the plane defined by the two linear edges of the semi-cylindrical cathode. A strip 16 has a different illuminance than the rest of the emitter. The strip consists of the shadow of the collector 13. This figure illustrates the fact that a difference between the illuminance of the strip 16 and the rest of the 15 emitter is sufficient to effect oscillation. It has been observed that with a distant light forming a somewhat diffuse shadow, a different mode of oscillation exists which is lower in frequency and in which the wave form is typically non-sinusoidal. However, in this mode the frequency is less stable with changes in field intensity.

A resistive load has been shown in all the figures with the emitter being grounded to reduce stray field pickup. It has also been found that if the output is taken across a choke coil which filters out the lower frequencies, oscillations in excess of 2.5 megacycles can be observed which also change in frequency with light intensity. It is significant that the load does not affect the frequency of oscillation and therefore a tuned circuit could be used in place of the resistive load if desired.

As previously mentioned, the device has a constant amplitude output when the load matches the impedance of the device over the range of operation. Since the device is believed to rely for its operation on an inter-electrode rotating electron plasma with which the electrodes are capacitively coupled, the effective impedance of the device changes with the magnetic field strength. The effective impedance is also inversely proportional to the illuminance. Bearing this in mind, it will be apparent that a photo resistor, such as a cadmium sulfide element, or a pair of photo tubes oppositely connected in parallel, would provide the required impedance matching if their illumination varied in the same manner as the illumination of the present device. An arrangement working on this principle is shown in FIGURES 4 and 4A. The device is identical to that shown in FIGURE 3 and its load consists of two photo tubes 19 and 20 oppositely connected in parallel, the output 18 being taken across these photo tubes. The photo tubes are illuminated by the light source L.S. which illuminates the device. Although shown on the opposite side of light source L.S., the photo tubes 19 and 20 could, of course, be positioned on the same side of the light source. By using a photo resistor which has the same conductivity in either direction, the arrangement of FIGURE 4A is provided in which a single photo resistor 19A replaces the two photo tubes required in the circuit of FIGURE 4. The circuit is otherwise identical to the oscillator circuit of FIGURE 4.

FIGURE 6 illustrates another important aspect of the present invention. If the light source L.S. passed through a slit in the plate 17 and focused on one edge of the cathode 12 of a photo-tube, oscillations are produced at the output 18 across the load resistor R. If, in addition, there is a general illumination of the cathode 12 by background illumination, such as a bulb 22 and a diffusing screen 23, the frequency of the output can be controlled by the level of illumination of the diffuse source as well as the intensity of the strip source. Thus a mixer is provided which can be used as a modulator or a demodulator. For example, a circuit, such as an amplifier or the like, can be used to vary the intensity of the bulb 22 with variations in amplitude of an input signal.

While the oscillator is generally described as preferably operating with zero anode potential, the amplitude of the output may be increased to a maximum of several hun-

dred millivolts with two or three volts positive potential on the anode. A small positive potential of several volts, as indicated in FIGURES 2 and 3, increases the dynamic range of the oscillator, enhances the stability and increases the output amplitude. Variations in the anode potential over a range of 1 to 5 volts produces very little change in output frequency. Other factors such as the frequency (color) of the light source, the character of the light pattern and the sharpness or diffusion of the light image, all affect the characteristics of the oscillator. Also the invention is applicable to use with other types of radiant energy, such as infrared, ultra-violet or X-ray radiation, as well as alpha and beta particle radiation, depending on the spectral sensitivity of the emitter.

What is claimed is:

1. An oscillator for generating an alternating output signal comprising a cathode having an electron emissive surface sensitive to incident radiant energy, an anode positioned in front of the cathode electron emissive surface, means for enclosing the anode and cathode in a vacuum region, means for directing radiant energy in an elongated pattern on the electron emissive surface of the cathode to provide an energy discontinuity on the cathode surface, means for producing a magnetic field extending in a direction transverse to the elongated direction of the energy discontinuity, and means including an output load impedance connected between the anode and the cathode across which the oscillating output signal is generated.
2. Apparatus as defined in claim 1 wherein said means connected between the anode and cathode includes conductors for directly connecting the output load impedance to the anode and cathode.
3. Apparatus as defined in claim 1 wherein said means connected between the anode and the cathode includes a potential source of not more than a few volts connected in series with the load impedance between the anode and cathode to provide a small DC voltage between the anode and cathode.
4. An oscillator circuit comprising a vacuum photo-tube having a light sensitive emitter and collector within an enclosure, means for illuminating a portion of the emitter surface with an elongated area with a different level of illumination than the adjacent portion of the emitter, means producing a magnetic field extending transverse to the elongated area in the region between the emitter and collector, and a load impedance connected between the emitter and collector, the oscillator output signal being derived across the impedance.
5. Apparatus as defined in claim 4 wherein said means illuminating a portion of the emitter includes means for forming an elongated strip of light focused on the emitter.
6. Apparatus as defined in claim 4 wherein said means illuminating a portion of the emitter is positioned to cast a shadow of the collector on the surface of the emitter.
7. Apparatus as defined in claim 4 wherein said impedance is a resistor.
8. Apparatus as defined in claim 4 wherein said impedance is a light sensitive element having an effective resistance that changes with light intensity.
9. An oscillator comprising a vacuum photo-tube having a semi-cylindrical cathode and a rod-shaped anode within an enclosure, means for directing a beam of light at the cathode, said beam of light being formed to illuminate only a portion of the cathode surface, means for producing a constant magnetic field in a direction parallel to the plane defined by the parallel straight edges of the semi-cylindrical cathode and perpendicular to the rod-shaped anode, and a load impedance connected to the anode and the cathode.
10. Apparatus as defined in claim 9 further including means for applying a small DC potential between the cathode and the anode.
11. Apparatus as defined in claim 9 wherein the load impedance is a resistor substantially matching the anode-cathode impedance of the photo-tube.

12. Apparatus as defined in claim 9 further including means simultaneously providing illumination of the cathode with incident energy at a different energy level than the beam of light.

13. Apparatus as defined in claim 12 further including means for varying the intensity of illumination of said illumination providing means.
